DIAPHRAGM PUMP

JB Johnson, Tyler, Tex., assignor of twenty-four per cent to Wilford C. Thompson and twenty-four per cent to Pickens Morris, both of Tyler, Tex.

Application November 17, 1949, Serial No. 127,919

10 Claims. (Cl. 103—5)

1

This invention relates to fluid pumps and more particularly to a diaphragm type pump incorporating novel drive and control features and being particularly adapted for use where space is at a premium.

Diaphragm type pumps are old and well known and possess numerous advantages such as relatively low construction cost, relatively large capacity for a given physical size, simplicity of structure and reliability in operation. This invention retains all of the prior advantages and includes refinements not heretofore utilized in this type of pump.

It is therefore an object of this invention to provide a diaphragm pump incorporating novel control means whereby the operation of the pump may be completely stopped without in any way interrupting the drive thereto and in which the output capacity of the pump may be varied between zero and maximum all by a single easily operated manual or automatic control.

It is a further object of the invention to provide a diaphragm pump in which a plurality of individual units may be conveniently stacked to provide a multiple chamber pump.

It is a further object of the invention to provide a diaphragm pump which may be conveniently manufactured as a multi-stage pump in order to produce relatively high pressures while still maintaining the inherent advantages of a diaphragm pump.

It is a further object of the invention to provide a diaphragm pump of relatively simple and economical construction in which it is unnecessary to maintain close dimensional tolerances and which provides ready accessibility for maintenance and repair when such becomes necessary.

Further objects and advantages of the present invention will be apparent from the following description taken in conjunction with the accompanying drawings; wherein:

Fig. 1 is a longitudinal sectional view showing the internal structure of the diaphragm pump of this invention and the associated drive and control mechanism;

Fig. 2, a top plan view of the pump shown in Fig. 1 with the cover plate removed;

Fig. 3, a fragmentary longitudinal sectional view showing a plurality of pump units stacked to provide a multiple chamber pump;

Fig. 4, a fragmentary longitudinal sectional view similar to Fig. 3 showing a plurality of stacked progressively smaller units to provide a multi-stage diaphragm pump;

Fig. 5, a fragmentary view with parts in section

2

for greater clarity showing a portion of the drive mechanism and associated control means; and,

Fig. 6, a sectional view showing the details of one of the valves incorporated in the diaphragm of the pump.

With continued reference to the drawings, there is shown in Fig. 1 a diaphragm pump including a main pump body 10 which may be conveniently constructed in the form of a relatively thick circular plate although this body may be of any form desired. Body 10 is provided in its upper face with a recess having an angularly disposed peripheral wall 11, the central portion of the body 10 being counterbored at 12 and 13 for a purpose to be presently described. A cover plate 14 is provided with a frusto-conical recess 15 in its lower face which together with the recess in the body 10 constitutes the pump chamber. Cover plate 14 is adapted to be positioned on the body 10 and be secured thereto by screw threaded fastening means or the like 16.

A diaphragm 17 of suitable flexible material is clamped between body 10 and cover plate 14 adjacent the periphery thereof, this diaphragm extending completely across the pump chamber and being clamped to a reciprocating valve plate 18 by a clamping plate 19 provided with a plurality of apertures 20 and a central portion 21 having a recess 22 therein for a purpose to be presently described. Clamping plate 19 is secured to valve plate 18 by a plurality of screw threaded fasteners or the like 23.

Valve plate 18 is provided with a plurality of apertures 24, these apertures terminating in counterbores 25 adjacent the upper surface of the plate. Positioned in each of these counterbores is a valve 26 shown in detail in Fig. 6.

Valve 26 comprises a stamped sheet metal body 27 of stepped construction, there being a plurality of slots or apertures 28 therein to permit the passage of fluid through the valve. Valve body 27 is so formed as to provide a centrally located aperture 29, the side wall of which terminates inwardly of the body 27 to provide a valve seat 30. Positioned upon this seat is a valve member 31 in the form of a disc which is normally held in engagement with the seat 30 by a compression spring 32 engaging the valve member 31 and the body 27. A portion of the body 27 provides an annular flange 33 which may be conveniently utilized to secure the valve 26 in position in the valve plate 18. This operation is accomplished by seating the valve 26 in the counterbore 25, there being a plurality of screw threaded fasteners or the like 34 positioned around the

counterbore with a portion of each head of the fasteners 34 engaging the flange 33 and the upper surface of the plate 18 to securely clamp the valve 26 in position within the counterbore 25.

Valve plate 18 is provided on its lower surface with a centrally located circular boss 35 having a generally hemispherical recess 36 therein, the outer surface of the boss 35 being provided with a tapered threaded portion 37 adapted to receive a taper threaded nut 38. This structure provides a convenient means for attaching the diaphragm 17, valve plate 18 and clamping plate 19 to the drive mechanism to be presently described.

In order to conveniently mount or support the pump body 10 and associated parts and also to house the driving mechanism there may be provided a tubular member 39 having a flange 40 at one end secured to pump body 10 by screw threaded fastening means or the like 41, the opposite end of tubular member 39 terminating in a flange 42 having apertures 43 therein for receiving fastening means to securely mount the pump upon a supporting structure.

The novel drive mechanism incorporated in this pump comprises a cup-shaped cylindrical member 44 slidably received within the tubular member 39 cylindrical member 44 also slidably receiving a second cup-shaped cylindrical member 45 to provide a telescoping assembly. Positioned within the members 44 and 45 and in engagement with their end walls is a compression spring 46 which serves to transmit compressive force from member 45 to member 44.

Member 44 is provided with an axially extending rod-like portion 47 terminating in a ball 48 received in the hemispherical recess 36 in boss 35. Ball 48 is loosely clamped in position by taper threaded nut 38 to provide a ball and socket joint.

Cylindrical member 45 terminates at its lower end in an axially extending rod-like portion 49 which is slidably received in an aperture 50 in end closure plate 51 which may be secured in place in a counterbore 52 in the end flange 42 by screw threaded fastening means or the like 53. Aperture 50 together with the cylindrical inner wall of the tubular member 39 provides a guide means for the drive assembly. However, close manufacturing tolerances need not be maintained for these parts since all that is necessary is a relatively loose sliding fit.

In order to prevent leakage between the pump chamber and the interior of tubular member 39, a sealing diaphragm 54 may be clamped in counterbore 13 in pump body 10 by a clamping plate 55 secured by screw threaded fastening means or the like 56. Sealing diaphragm 54 is provided with a centrally located aperture received over the boss 35 and is clamped in position thereon by taper threaded nut 38. This structure provides an effective seal between the pump chamber and the interior of tubular member 39 and prevents any leakage of fluid therebetween.

In order to vent any fluid pressure which may build up within the telescoping cup-shaped members 44 and 45 and also to permit the introduction of lubricant thereto member 44 may be provided with a vent opening 57 and member 45 with a vent opening 58. Likewise, closure plate 51 may be provided with vent openings 59 whereby lubricant may be introduced to the assembly and fluid pressure vented therefrom.

The above described pump may be driven in any desired manner but for purposes of illustration only there is shown a drive shaft 60 having 75 its lowermost position at which time return spring

a pulley 61 mounted thereon and engaged by a drive belt 62. Also mounted on shaft 60 is a cam 63 which engages a cam follower 64 secured to rod-like extension 49 on cup-shaped member 45 by screw threaded fastening means or the like 65. Obviously if desired the rod 49 could be operated by a rocker arm engaging the end thereof or by a conventional crank and pitman arrangement and also rod 49 if desired might be connected directly to the piston of a reciprocating motor. Since the particular means for actuating the rod 49 forms no part of this invention, it is deemed unnecessary to illustrate or describe other than one conventional means.

The suction chamber of the pump of this invention is provided by the recess in the pump body 10 and in order to permit the flow of fluid thereto there is provided a screw threaded bore 66 which may threadedly receive an inlet valve 67. Valve 67 is provided with a valve member 68 which is normally urged to closed position by a compression spring 69. However, upon upward movement of the diaphragm 17 to create a vacuum within the suction chamber the pressure of fluid on the outer surface of valve member 68 will move the same inwardly against the action of spring 69, thus permitting the flow of fluid to the suction chamber.

The recess 15 in the cover plate 14 provides a compression chamber and in order to conduct compressed fluid therefrom there is provided in the cover plate 14 a screw threaded bore 70 in which is threadedly received an outlet valve 71. Valve 71 is provided with a valve member 72 which is normally held in closed position by a compression spring 73, this valve preventing flow of fluid from the exterior of the pump into the compression chamber but opening against the action of spring 73 to permit the flow of compressed fluid therefrom.

In order to insure return of the diaphragm 17 and associated parts to lowermost position there is provided a return spring 74 with one end positioned in recess 22 in clamping plate 19 and with the opposite end positioned in a recess 75 in cover plate 14.

In operation upon rotation of the shaft 60 and associated cam 63, the rod 49 and cup-shaped member 45 will be reciprocated due to the engagement of cam 63 and cam follower 64. This reciprocatory movement will be transmitted in one direction to cup-shaped member 44 by compression spring 46 which will serve to move the valve plate 18, diaphragm 17 and clamping plate 19 upwardly in the pump chamber to compress fluid above the diaphragm and force the same outwardly through outlet valve 71. At the same time a partial vacuum will be created below the diaphragm causing fluid to flow into the suction chamber through valve 67. Upon return movement of the diaphragm under the action of spring 74 the valve members 31 in valves 26 will open against the action of springs 32 to allow fluid in the suction chamber to flow upwardly through slots 28 into the compression chamber thus recharging the same with fluid to permit repetition of the pumping cycle.

Obviously the compression spring 46 may be so calibrated that the pressure developed in the compression chamber will be governed thereby since if such pressure exceeds the compression strength of spring 46 this spring will yield and the diaphragm and associated parts will remain stationary until cup-shaped member 45 returns to

14 will return the diaphragm to lowermost position. This structure determines the maximum pressure developed by the pump and also affords a safety device in the event the compression chamber becomes filled or partially filled with liquid or other comparatively incompressible substance whereby a positive movement of the diaphragm would result in damage to the parts with possible rupture of the diaphragm or breakage of the associated elements.

Since it is often desirable to discontinue operation of the pump without stopping the mechanism which supplies motive power thereto and also since it is often highly desirable to provide means whereby the capacity of the pump may be varied, a simple efficient and novel control mechanism is provided which is shown in detail in Fig. 5 and applied to the pump assembly in Fig. 1.

This control mechanism comprises a bell crank lever 76 which may be conveniently pivoted at 77 on ears 78 extending from the wall of the tubular member 39, a portion of the bell crank lever 76 extending through an aperture 79 in the wall of the tubular member 39. The inner end of the bell crank lever 76 is provided with a yoke 80, the arms thereof being disposed on each side of the extension 47, the yoke arms terminating in enlarged portions 81 providing bearing surfaces to engage the lower surface of taper threaded nut 38. The opposite end of bell crank lever 76 is provided with an apertured portion 82 adapted to receive an operating or control wire 83 which is clamped in position by a screw threaded fastening means or the like 84. The control wire 83 may extend through a flexible sheath 85 to a point convenient to the operator, the wire 83 being provided with a finger engaging knob (not shown) which may be utilized for controlling operation of the pump. Sheath 85 may be secured in position by one or more sheet metal clips 86 fixed in place by screw threaded fastening means or the like 87.

Upon operation of control wire 83 to rotate the bell crank lever 76 clockwise as viewed in Fig. 5, the enlarged portion 81 will bear against the nut 38 and raise the diaphragm 17 and associated parts to uppermost position thereby preventing reciprocation of the same under the action of rod 49 and compression spring 46. This will result in reducing the pump capacity to zero and the pump will remain in inoperative condition until wire 83 is actuated to move bell crank lever 76 in counterclockwise direction whereupon the diaphragm 17 and associated parts will be reciprocated through a path of travel depending upon the position of enlarged portion 81. If the movement of the bell crank lever 76 is sufficient to move the enlarged portion 81 entirely out of contact with nut 38 then the diaphragm 17 and associated parts will move through their full path of travel and the pump will deliver its maximum capacity whereas if the enlarged portion 81 occupies some intermediate position this will serve to block downward movement of the nut 38 and diaphragm 17 whereby the path of travel will be some intermediate value between maximum and zero. This structure results in providing an infinite variation in the capacity of the pump between zero and maximum and obviously means will be provided to properly clamp the control wire 83 in order to retain the bell crank lever 76 and enlarged portion 81 in the desired position.

Obviously various modifications of this control mechanism may be employed such as a cam in engagement with the nut 38, the cam having a proper contour to accomplish the desired varia-

tion in diaphragm movement. The basic principle, however, would be the same regardless of what specific mechanism was employed and the structure disclosed in Fig. 5 is by way of illustration only.

The pump structure above described is readily adapted for use in a multiple pump structure such as that shown in detail in Fig. 3 and in which the pump body 10 is identical with that shown in Fig. 1 and in which the cover plate 88 is slightly modified from the cover plate 14 shown in Fig. 1. In this modification the cover plate 88 is provided with a central bore 89 and a counterbore 90 which bore and counterbore serve to receive the mechanism linking adjacent units of the pump together. Clamping plate 19 is provided at its center with a boss 91 similar to the boss 35 on the valve plate 18, boss 91 being provided with a hemispherical recess 92 and a threaded tapered outer surface 93. Recess 92 serves to receive the ball shaped end 94 of a connecting rod 95, the ball 94 being loosely clamped in position by a taper threaded nut 96 engaging the threads 93. Nut 96 likewise serves to clamp a sealing diaphragm 97 in position, the outer portion of this diaphragm being clamped in counterbore 90 by a clamping plate 98 and screw threaded fastening means or the like 99. This diaphragm serves to effectually seal the bore 89 against the passage of fluid from the compression chamber of the pump. The cover plate 88 is provided with a screw threaded bore 100 for receiving outlet valve 71 identical with that provided in the pump shown in Fig. 1. This comprises one unit of the multiple pump and operates to receive and discharge fluid under pressure in exactly the manner above described in connection with the operation of the pump of Fig. 1.

The second unit of the pump is identical with that just described, this pump being operatively connected to the first unit by the connecting rod 95, the upper end of which is provided with a ball-like connecting member 101 which is received in the hemispherical recess 36 of the boss 35. As many units as desired may be stacked one on the other, the only limiting factor being space and the operating power available, the upper or final unit being identical with the pump shown in Fig. 1, the cover plate 14 serving to terminate the assembly with the fastening means 16 being elongated and extending through the entire assembly to the pump body 10 whereby the complete stack is accordingly clamped in operative relationship. This pump may be utilized to handle a plurality of different fluids for different purposes or may serve to supply a single fluid at an increased volume.

The pump of this invention also adapts itself to providing a multi-stage pump, the details of which are shown in Fig. 4. In this modification the pump body 10 is identical with that described in connection with the previous modifications and the cover plate 102 for the first stage of the pump is provided with a central aperture and sealing mechanism as described in connection with the modification of Fig. 3, this cover plate being further modified to provide screw threaded bores 103 for threadedly receiving discharge valves 104 which are similar to discharge valves 71 previously described.

The pump body 105 for the second stage of the pump in addition to the central aperture and sealing means as provided in pump body 10 also has a plurality of inlet ports 106 which are positioned to register with the bores 103 in the cover

plate 102 when the body 105 and plate 102 are positioned in stacked relationship, ports 106 serving to receive high pressure fluid from the compression chamber of the first stage of the pump and deliver this fluid to the suction chamber of the second stage. The cover plate 102 for the second stage is identical with the cover plate 102 for the first stage with the exception that the diameter thereof is less to correspond with the diameter of the pump body 105 whereby the volume of the pump chamber is reduced since the volume of the fluid received in this second stage is less than the volume of fluid received in the suction chamber of the first stage, this reduction in volume arising due to the compression of the fluid in the first stage. Likewise, the pump body 105 of the third stage is of reduced diameter to correspond with the diameter of the cover plate 102 of the second stage whereby the volume of the pump chamber in the third stage is still further reduced. The cover plate 107 is similar to cover plate 14 except for size and is provided with a central recess 74 to receive one end of return spring 75 and is also provided with a screw threaded bore 70 to receive discharge or outlet valve 71.

The operation of the three stage pump is similar to that described above in connection with the modification shown in Fig. 3 except that fluid is received into the pump through inlet valve 67 whereupon it is compressed in the first stage and discharged therefrom into the second stage where it is further compressed and discharged into the third stage, the third stage providing the final compression and discharge through the outlet valve 71.

Obviously the control mechanism described in connection with the modification of Fig. 1 is equally applicable to the modifications of Figs. 3 and 4 and together with these modifications provides a very efficient and versatile pump mechanism. Due to the use of diaphragm type pistons very little machine work is required in fabricating the device and practically no close machine tolerances need be adhered to. Consequently, a very low cost construction is possible and the unit will operate to deliver a maximum quantity of fluid and yet occupy a minimum of space. Likewise, in view of the particular nature of the construction a relatively simple control mechanism is possible whereby the output of the pump may be varied from zero to maximum without in any way effecting the operation of the drive mechanism and likewise it has been rendered very convenient to provide means for preventing damage to the pump due to the presence of liquid or other relatively incompressible fluid in the pump chamber.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. A diaphragm pump comprising a body, a cover member secured to said body, said body and cover member being recessed to form a pump chamber, a diaphragm between said body and said cover member and extending across said chamber, an inlet valve in said body, an outlet valve in said cover member, a valve plate secured to said diaphragm, valves in said valve plate for controlling the flow of fluid from one side of said

diaphragm to the other, a support for said pump comprising a tubular member secured to said body, sealing means between said chamber and the interior of said tubular member, a drive mechanism for reciprocating said diaphragm comprising a first cup-shaped member slidably disposed in said tubular member, a second cup-shaped member telescopically received within said first cup-shaped member, a calibrated compression spring disposed within said cup-shaped members, means connecting said first cup-shaped member and said valve plate, means for reciprocating said second cup-shaped member whereby said diaphragm will be reciprocated through said spring, the pressure developed in said chamber being dependent upon the compression strength of said spring and a return spring engaging said diaphragm and said cover member.

2. A diaphragm pump comprising a body, a cover member secured to said body, a recess in said body and said cover member forming a pump chamber, a diaphragm clamped between said body and said cover member and extending across said chamber, an inlet valve in said body, an outlet valve in said cover member, a valve plate secured to said diaphragm, valves in said valve plate for controlling the flow of fluid from one side of said diaphragm to the other side, a support for said pump comprising a tubular member secured to said body, sealing means between said chamber and the interior of said tubular member, a drive mechanism for reciprocating said diaphragm comprising a first member slidably disposed in said tubular member, a second member slidably disposed in said tubular member and spaced from said first member, a calibrated compression spring disposed between said members, means connecting said first member and said valve plate, means for reciprocating said second member whereby said diaphragm will be reciprocated through said spring, the pressure developed in said chamber being dependent upon the compression strength of said spring and a return spring engaging said diaphragm and said cover member.

3. A diaphragm pump comprising a body, a cover member secured to said body, a recess in said body and said cover member forming a pump chamber, a diaphragm clamped between said body and said cover member and extending across said chamber, an inlet valve in said body, an outlet valve in said cover member, a valve plate secured to said diaphragm, valves in said valve plate for controlling the flow of fluid from one side of said diaphragm to the other side, a support for said pump comprising a tubular member secured to said body, sealing means between said chamber and the interior of said tubular member, a drive mechanism for reciprocating said diaphragm comprising a first member slidably disposed in said tubular member, a second member slidably disposed in said tubular member and spaced from said first member, a calibrated compression spring disposed between said members, means connecting said first member and said valve plate, means for reciprocating said second member whereby said diaphragm will be reciprocated through said spring, the pressure developed in said chamber being dependent upon the compression strength of said spring.

4. A diaphragm pump as defined in claim 1 in which said sealing means comprises a diaphragm clamped to said body and to said valve plate in fluid tight relationship.

5. A diaphragm pump comprising a body and

a cover member recessed to provide a pump chamber therebetween, a diaphragm within said chamber, an inlet valve in said body, an outlet valve in said cover member, valve means associated with said diaphragm for controlling the flow of fluid from one side of said diaphragm to the other side, a support for said pump comprising a tubular member secured to said body, means for reciprocating said diaphragm comprising a first cup-shaped member slidably disposed in said tubular member, a second cup-shaped member telescopically received within said first cup-shaped member, a calibrated compression spring disposed within said cup-shaped members, means connecting said first cup-shaped member and said diaphragm, means for reciprocating said second cup-shaped member whereby said diaphragm may be reciprocated by said spring, the pressure developed in said chamber being dependent upon the compression strength of said spring.

6. A diaphragm pump comprising a body and a cover member recessed to provide a pump chamber therebetween, a diaphragm within said chamber, yieldable means for reciprocating said diaphragm and a control means for said pump comprising a pivotally mounted bell crank lever, one end thereof terminating in a yoke, enlarged bearing portions upon said yoke constructed and arranged to engage said diaphragm, a control wire secured to the opposite end of said bell crank lever whereby upon operation of said control wire to pivot said bell crank lever said bearing portions will engage said diaphragm to prevent movement thereof or engage said diaphragm to permit limited movement thereof, said control means being effective to control the capacity of said pump between zero and maximum.

7. A multiple diaphragm pump comprising a body and a cover member recessed to provide a pump chamber therebetween, a diaphragm disposed in said chamber, a second body and cover member providing a second pump chamber therebetween, a second diaphragm disposed in said second pump chamber, a third pump body and cover plate providing a third pump chamber therebetween, a third diaphragm disposed in said third pump chamber, said pump bodies and cover members being secured together in stacked relationship, a connecting rod connecting said first and second diaphragms, a second connecting rod connecting said second and third diaphragm, seal-

ing means between said first pump chamber and said second pump chamber, sealing means between said second pump chamber and said third pump chamber and yieldable means for reciprocating said diaphragms whereby the pressure developed in each pump chamber will be dependent upon the compression strength of said yieldable means.

8. A multiple diaphragm pump as defined in claim 7 including control means for reducing the output of said pump to zero or for infinitely varying the output between zero and maximum.

9. A multiple stage diaphragm pump comprising a body and cover member recessed to provide a pump chamber therebetween, a diaphragm disposed in said chamber, a second pump body and a cover member providing a pump chamber of reduced volume therebetween, a second diaphragm in said second chamber, a third pump body and cover member providing a third pump chamber therebetween of still further reduced volume, a third diaphragm disposed in said third chamber, connecting rods connecting said first and second diaphragm, a second connecting rod connecting said second and third diaphragms, sealing means between said first and second pump chambers, sealing means between said second and third pump chambers, valved ports connecting said first and second pump chambers, valved ports connecting said second and third pump chambers, an inlet valve to said first chamber, an outlet valve from said third chamber and yieldable means for reciprocating said diaphragms whereby the pressure developed in said third pump chamber is dependent upon the compression strength of said yieldable means.

10. A multiple diaphragm pump as defined in claim 9 including control means for reducing the output of said pump substantially to zero or for infinitely varying the output substantially between zero and maximum.
